PHILLIPS THOMAS, OF EDGEWOOD PARK, PENNSYLVANIA, ASSIGNOR TO WESTINGHOUSE ELECTRIC & MANUFACTURING COMPANY, A CORPORATION OF PENNSYLVANIA.

GLOW-DISCHARGE TRANSMITTER.

Application filed November 14, 1922. Serial No. 600,823.

My invention relates to telephone systems and apparatus and particularly to improved sound-wave translating devices.

In its broadest aspect, an object of my invention is to provide a translating device which is capable of effecting an interchange of energy between a fluid medium subject to vibratory motion and an electrical circuit subject to pulsating electrical currents.

More specifically an object of my invention is to provide a translating device of the class described, wherein sound waves are faithfully translated into correspondingly modulated electrical energy without impairing the quality, tone and quantity of the translated energy.

Another object of my invention is to provide a telephone translating apparatus which embodies no moving parts and more especially one wherein the usual vibratory diaphragm may be eliminated.

A further object of my invention is to provide a sound wave translating device which is characterized by its simplicity of design and operation and which lends itself to inexpensive methods of manufacture, wherein the several parts may be easily made by existing automatic machinery and may be readily assembled with a minimum expenditure of time and of money.

In practicing my invention, I provide a translating device comprising a pair of spaced electrodes and an energizing circuit therefor designed to establish a glow discharge between the pair of electrodes. I have found that the voltage-current characteristic of the glow discharge varies in accordance with variations in the pressure of the medium surrounding the discharge.

In a preferred form of embodiment of my invention, the current through the discharge is maintained substantially constant and the variations in voltage across the discharge electrodes incident to the presence of sound waves are translated into amplified current variations by means of a repeater device of well known design.

In a modified form of my invention, the voltage across the discharge electrodes rather than the currents traversing the path therebetween is maintained substantially constant to allow pressure variations to effect corresponding variations in the intensity of the currents in the discharge. The cur-

rent variations may be translated by means of a transformer, into potential variations and impressed upon the input terminals of a repeater device, as in the preferred embodiment just mentioned.

In the development of my invention, considerable difficulty was experienced in establishing and maintaining a glow discharge between the discharge electrodes. Furthermore, the discharge, when once established, was likely to be very noisy in operation. After considerable experimental work, involving tests of many well known materials as discharge electrodes, I have found that discharge electrodes of copper permit the easy establishment and maintenance of a glow discharge which is very quiet in operation. The discharge between the electrodes may be made more steady by employing pointed electrodes, since the discharge normally tends to operate between points.

Further difficulty was encountered in the tendency for the discharge to assume, at times, an insensitive condition, wherein the voltage-current characteristic is only slightly affected by variations in pressure. As the electrodes age in service, a condition arises where the low sensitive state becomes permanent. This difficulty was overcome by causing the discharge to operate in a magnetic field which is parallel to the path of the discharge.

A still further difficulty was encountered in the employment of shielding means for the supply conductors leading to the discharge electrodes, inasmuch as the glow discharge tends to become unsteady by the use of the same. This difficulty is overcome by inserting a relatively high impedance in one or more of said discharge supply conductors immediately adjacent to the corresponding discharge electrodes.

With these and other objects and applications in view, my invention further consists in the nature, the mode of operation and the constructional details hereinafter described and claimed and illustrated in the accompanying drawing, wherein:

Figure 1 is a view, partially diagrammatic and partially structural, of circuits and apparatus embodying a preferred form of my invention;

Figure 2 is an enlarged detail view showing the discharge electrodes of Fig. 1 and

illustrating the several component parts of a glow discharge;

Fig. 3 is a view similar to Fig. 1 but showing a modification.

5 In the form of embodiment of my invention shown in Fig. 1, a pair of pointed discharge electrodes, 1 and 2 consisting, preferably of copper material, are secured, respectively, to adjacent ends of a pair of magnetizable members 3 and 4. The magnetizable members 3 and 4 are, in turn, connected by conductors 5 and 6, respectively, to the plus and minus terminals of a source of direct-current energy (not shown). As previously stated, it was found that a glow discharge could be easily established and maintained between electrodes of copper, which was practically impossible for the other materials, as manganese, iron and nickel. 10 Subsequent experimental work with tungsten, silver and platinum brought out the fact that a glow discharge could be established and maintained between electrodes of such materials but that such discharge was 15 very noisy, in comparison with the one established between copper electrodes.

A resistor 7 may be connected in series-circuit relation with the conductor 6 and serves to maintain the current there-through substantially constant, not withstanding slight variations in the impedance of the glow-discharge path. In practice, it was found that the electromotive force of the energy source (not shown) may be on 20 the order of 6000 volts and that the resistance of the resistor 7 may be on the order of 30 a megohm.

When the discharge electrodes 1 and 2 are separated a certain amount, say $\frac{1}{16}$ of 40 an inch for a system having the constants just indicated, a glow discharge is established therebetween which differs in several important respects from the ordinary type of arc discharge. That is to say, in the 45 glow discharge, the electrodes 1 and 2 remain relatively cool during operation; there is substantially no vaporization or melting or burning or disintegrating of the electrodes; the hot spot peculiar to the ordinary arc is entirely absent; and the discharge takes place in a steady, quiet and smooth manner. The latter characteristic is of especial importance since the variations in the voltage-current characteristic of the 50 discharge for fluctuations of the same may be comparable to the characteristic variations caused by sound waves, as will be apparent more fully hereinafter.

The glow discharge just mentioned 55 comprises the following portions arranged in their respective order between the negative electrode 2 and the positive electrode 1; namely, a negative light 8, which is in immediate contact with the negative electrode 60 2; a cathode dark space 9, sometimes known

as Crooke's dark space; a cathode glow 11; a Faraday dark space 12; and a positive or anode column 13, which terminates on the positive electrode 1, all as indicated in Fig. 2.

As previously pointed out, it has been observed that, when a glow discharge is established, the voltage-current characteristic thereof varies with pressure. Since the resistance of the resistor 7 is of such value as 75 to maintain the currents therethrough substantially independent of slight potential variations, in the glow discharge, the effect of pressure variations, as produced by sound waves, is to cause corresponding potential variations across the discharge electrodes 1 and 2 having a wave form corresponding to that of the pressure variations. The potential drop across the discharge electrodes 1 and 2 is thus composed of a 80 constant component, namely the so-called "quiet voltage drop" and an alternating component which corresponds to the sound waves.

The alternating component of voltage 90 just mentioned may be translated into amplified currents of similar wave form by impressing the same through conductors 14 and 15 upon the grid and filament elements 16 and 17, respectively, of a three-electrode 95 vacuum tube 18, including in addition a plate element 19.

A condenser 21, having a negligible impedance to currents of sound-wave frequency, is included in the grid conductor 14 and serves to prevent the so-called "quiet voltage drop" across the discharge electrodes 1 and 2 from operating to effect the blocking of the tube 18. A grid leak resistor 22 may be included in a circuit 23 connected in shunt relation to the grid and filament elements 16 and 17 respectively, of the tube 18 in order to control the intensity of the negative charges which are accumulated on the grid 16. A source 24 of direct-current energy may be included in the grid-leak circuit 23 to provide for further adjustment of the grid potential to the best operating value for the tube 18.

A plate-filament circuit for the tube 18 includes a source 25 of direct-current energy, say 200 volts, and a high impedance coupling resistor 26. The potential variations, which are established across the resistor 26 following the variations in the characteristic of the glow discharge in the presence of sound waves, may be impressed by conductors 27 and 28 upon the input elements of a second amplifying device (not shown), or other circuit arrangement designed to employ modulated electrical energy.

As hereinbefore stated, it was found that the glow discharge at times assumed an insensitive state and that, as the electrodes

aged, a time was reached when the insensitive state became permanent. This undesirable characteristic was found to be avoided by establishing, in the immediate vicinity of 5 the discharge, a magnetic field which was parallel to the path of the same.

For purposes of illustration, I have shown one particular arrangement for establishing such magnetic field. The arrangement comprises the spaced magnetizable members 3 and 4 and a magnetizable yoke member 29 therefor, the former serving as pole pieces for the latter. The magnetizable yoke member 29 may be provided with an exciting 10 winding 31 which is energized from a source 32 of direct-current energy through an adjustable resistor 33. The magnetic circuit of the several magnetizable members thus contains an air gap 34 which includes the 15 space occupied by the glow discharge. Hence, a magnetic field is established which is parallel to the path of the glow discharge.

An additional advantage of the magnetic field is that it tends to decrease any variations 20 in the sensitivity of the discharge with frequency and to render the operation of the same substantially constant in the presence of air currents.

When operating my invention in the circuit 25 of a large transmitting station, it was found necessary to provide means for shielding the conductors leading to the discharge electrodes, as, for instance, by including the same in cables 35 having a metallic covering. However, it was then found that the 30 operation of the glow discharge was exceedingly unsteady, since the conductors and shields functioned as condensers, periodically discharging across the discharge electrodes and extinguishing the normal glow 35 discharge. The operation of the glow discharge was rendered steady by including a resistor 36 in one of the conductors, as, 40 immediately adjacent to the corresponding electrode 2. The grid-conductor 14 is connected to the discharge electrode 2 through the resistor 36.

Various forms of glow discharge have 45 been established in oxygen, hydrogen, carbon dioxide and other gases with the idea of studying the effect of different gases on the operation thereof. Such experiments as have been made seem to indicate that, for best results, nitrogen must be present in the medium immediately surrounding the discharge.

The arrangement shown in Fig. 3 is differentiated over that shown in Fig. 1 in the provision of a different supply circuit 37 for the discharge electrodes 1 and 2 said supply circuit having such low impedance that current variations, rather than potential variations, are established therein when the pressure in the vicinity of the discharge is varied. The supply circuit 37 now includes

a low-voltage source of direct-current energy (not shown) and the primary winding 38 of a transformer 39, the secondary winding 41 of which is connected by conductors 42 and 43 to the input terminals 16 and 17, 70 respectively, of the repeater device 18, in the manner indicated in Fig. 1. The operation of this figure is otherwise as indicated for Fig. 1.

In view of the foregoing, it is apparent 75 that my invention embodies a translating or amplifying device which is characterized by its simplicity of design and operation. Attention is directed to the absence of moving parts, a feature peculiar to the ordinary 80 telephone translating device and one introducing disadvantages well known to those skilled in the art. Other advantages of my invention will be apparent from a study of the foregoing description and the following 85 claims.

In order to insure that the discharge will be a glow discharge and will continue to be a glow discharge, and not change into an arc, I find that the source of potential must 90 be high and that a current limiting device must be used. In addition to the specific dimensions already stated herein, the following actual constructions are noted. In one specific embodiment of my invention, I 95 employed a source of somewhat more than 4000 volts with a resistance in series between it and the discharge device of approximately one megohm. In another specific embodiment of this invention, I employed a source 100 of 4200 volts, together with a current limiting device which restricted the current to one millimeter. The current limiting device used in this instance was a saturation tube.

A characteristic difference between the 105 glow discharge and the arc is found in the relation of current to voltage. In the arc the current is much greater and the voltage much smaller than in the glow discharge. Another characteristic difference is that with 110 the glow discharge the electrodes are relatively cool, never becoming incandescent, while with an arc the electrodes are hot and the cathode is usually more incandescent than any portion of the arc itself. 115

While I have described my invention as embodied in circuit arrangements having certain specific values and while I have shown only two forms of embodiment of my invention, it is apparent that various 120 changes and modifications may be made therein without departing from the spirit thereof. I desire, therefore, that only such limitations shall be imposed thereon as are indicated in the appended claims or are 125 demanded by the prior art.

I claim as my invention:

1. An amplifying device comprising a pair of spaced copper discharge electrodes, the space between said electrodes being open 130

to the atmosphere, means for establishing and maintaining a glow discharge therebetween, and means for establishing a magnetic field in the space intermediate said spaced electrodes.

2. In combination, a pair of spaced electrodes, a source of energy, conductors associating said electrodes and said energy source to provide for the formation of a glow discharge between said electrodes, means for shielding said conductors and means for preventing the resulting capacity of the condensers formed by said conductors and shielding means from operating to render unstable said glow discharge.

3. In combination, a pair of spaced electrodes, a source of energy, conductors associating said electrodes and said energy source to provide for the formation of a

glow discharge between said electrodes, means for shielding said conductors, and a resistor included in circuit with one of said conductors for preventing the capacity effects between said conductors and said shields from operating to render unstable said glow discharge.

4. In a glow-discharge device, a pair of pointed electrodes spaced apart with the points toward each other, said points being of copper, and means for maintaining a magnetic field in the space between said electrodes parallel to the line between said points.

In testimony whereof, I have hereunto subscribed my name this 10th day of November, 1922.

PHILLIPS THOMAS.
